UNITED STATES PATENT OFFICE.

LUTHER T. VELEN, OF WASHINGTON, DISTRICT OF COLUMBIA.

SHOCK-FORMING APPARATUS.

1,194,445.

Specification of Letters Patent. Patented Aug. 15, 1916.

Application filed September 19, 1912. Serial No. 721,303.

To all whom it may concern:

Be it known that I, LUTHER T. VELEN, a citizen of the United States, residing at Washington, District of Columbia, have invented a new and useful Shock-Forming Apparatus, of which the following is a specification.

This invention relates to shock-forming apparatus and consists in the novel construction and arrangement of its parts as herein-after shown and described.

The object of the invention is to provide an apparatus which is adapted to receive bundles against the opposite sides of one of its parts whereby the said bundles may be carried from an approximately horizontal position into a vertical position and bound at their upper portions into the form of a shock. After this is done the bundles are placed upon the surface of the ground in the form of a shock with its corner portions spread that the stalks may cure and also that the shock will have ample foundation upon which to sustain itself in case of storm or other similar disturbances.

In the accompanying drawings: Figure 1 is a side elevation of the shock forming apparatus. Fig. 2 is a rear elevation of a portion of the same with parts in section. Fig. 3 is a detail enlarged side elevation of a portion of the same. Fig. 4 is a plan view of a portion of the shock ejecting mechanism of the same. Fig. 5 is a plan view of a portion of the bundle spreading means of the same. Fig. 6 is an under view of some of the parts shown in Fig. 5. Fig. 7 is a perspective view of a bundle spreading arm forming part of the apparatus. Fig. 8 is a sectional view of stalk directing plates constituting parts of the apparatus. Fig. 9 is a top plan view of a needle operating mechanism of the apparatus. Fig. 10 is a rear elevation of the same. Fig. 11 is a sectional view of the same cut on the line 11—11 of Fig. 10. Fig. 12 is an enlarged plan view of a portion of the same. Fig. 13 is a detail enlarged section view of a collar and adjacent parts forming parts of the apparatus. Fig. 14 is a perspective view of said collar. Fig. 15 is a sectional view of a portion of the bundle assembling mechanism of the apparatus. Fig. 16 is a sectional view of a portion of said mechanism. Fig. 17 is a plan view of the motor and the mechanism employed for transmitting motion therefrom to the crank arm.

The shock forming apparatus includes a frame 1 which is supported at its rear portion upon an axle 2. The axle 2 is provided with an intermediate crank portion 3 and an arm 4 is supported upon the portion 3 of the axle 2 and normally occupies a position at an angle of 40 to 45 degrees to a horizontal. A bar 5 is pivotally connected at one end to the arm 4 and at its forward end is connected with a draft appliance (not shown). This is done for the reason that when the said draft appliance is backed or the animals attached are backed, the bar 5 is moved longitudinally and the arm 4 is turned through an arc of approximately 90°. This operation is accomplished with the axis of the axle 2 as a center of movement. This mechanism has been disclosed in detail in my copending application No. 449,330, filed August 19, 1908, and does not constitute, specifically, any part of the present invention. A dividing fork 6 is carried by an arm 7 which in turn is attached to the arm 4 and stalk-receiving cradles are pivotally supported at the opposite sides of the fork 6 and are adapted to receive the stalks in approximately horizontal positions and swing the same into vertical position, as the said fork is swung from its lowermost to its elevated position. These cradles form no part of the present invention but are covered in my Patent No. 981,336, dated January 10, 1911. In addition to the dividing fork 6, an auxiliary dividing finger 8 is employed, this finger being mounted in the manner hereinafter described, and remaining in place along sides of the fork during the movement of the bundles toward shock-forming position. The finger further remains in its dividing position long after the fork has resumed its normal position, and is not withdrawn until the final movement of the machine away from the completed shock. Secured to the axle 2 is a beveled gear segment 9 which meshes with a beveled pinion 10 at the lower end of a vertical shaft 11.

Extending vertically from the rear portion of the main frame 1 are two vertical bars 12 that preferably are rectangular in transverse section. At the upper ends of these bars is secured a horizontally disposed rectangular frame 13 and this framework serves as a support for the shock assembling and tying mechanism.

Arranged upon the end portions of the axle 2 and beyond the sides of the frame 1

are plates 14 which are adapted to turn with said axle when it is swung. Plates 15 are pivotally mounted behind the rear edges of the plates 14 and are inclined downwardly and are adapted to drag at their lower edges upon the ground. The said plates 15 serve as spreader boards and are of the same width as the plates 14 and arranged to receive the butt ends of a bundle during the movement of the stalks to the ground; the butt ends will be somewhat divided and separated. For this purpose the upper face of the plate 15 is provided with a plurality of angularly disposed butt-end engaging ribs 16 and at the rear edge of the plate are angular recesses 17 which allow the stalks between the ribs to drop to the ground and be held separated as they strike the ground. In addition to the ribs an auxiliary finger 18 is secured to the plate 14 and is adapted to swing with the same in order to further assist spreading the stalks. As the plates 14 will swing rearward and upward during the time that the shock is being passed from the apparatus to the surface of the ground, while the dividing board or plate 15 remains relatively stationary, it becomes necessary to provide an intermediate guide board and for this purpose a plate 19 is pivoted at its front edge to the rear edge of the plate 14, while the rear edge of the said plate 19 rests upon the upper face of the spreader board or plate 15. As the plate 14 swings upward the plate 19 will be carried to a point near the front of the under plate 15 and will form an inclined plane down which the butts of the stalks may travel in the direction of the plate 15. As the forward portion of the plate 14 moves in a downward direction which occurs during the shock-tying operation, the auxiliary plate 19 will slide down to its initial position over the spreader plate 15, but as this plate is formed of comparatively thin metal, it will simply pass under the stalks which remain on the said plate 15.

Projecting from the rear end of the main frame 1 is a plate 20, the opposite edges of which are provided with a series of openings 21 to permit adjustment of the pivot pins of a pair of shock-spreading levers 22. The levers extend out from under the opposite edges of the plate in a position at right angles to the plane of the machine, and these levers are so positioned with respect to the fingers 18 that as the forward plates 14 turn in an upward direction at their forward ends, the stalks which have been supported by the fingers 18 will be thrown to the rear of the levers 22, while the stalks upon the forward portions of the plates 14 will slide down the spreader plates 15, as above described in front of the levers 22 so that as the unbound shock now

stands on the ground, its base is divided into four columns which represent approximately corner bundles. The next step in the operation consists in bringing the upper portions of the stalks together and tying the four columns near the top to form a shock. When the stalks are brought to upright position, in the manner as indicated, the fork 6 and finger 8 divide the upper portions of the stalks from each other, while the butt ends of the stalks are divided into four columns or parts by the plate 20 the levers 22 and the fingers 18. Also some of these stalks will be upon the surface of the ground, while others have not yet moved down below the lower edge of the spreader plate 15, the more effectually to spread the columns of the stalks as indicated in dotted lines in Fig. 1 of the drawings.

On the vertical bars 12 of the rear frame is guided a vertically adjustable frame 23. This frame carries the mechanism for gathering the bundles of stalks in the form of a shock, for tying the shock and for effecting the discharge of the finished shock from the machine. The upper portion of the frame is approximately rectangular in form and is provided with a cross bar 24 and on top of the frame is a plate 25. The plate and the cross bar are provided with centrally disposed alining openings for the passage of a pin 26 having an enlarged lower end that fits within a correspondingly large portion of the opening in the bar 24. To the upper end of this pin is secured an eye 27 from which extends a cable 28, said cable being guided over a pair of sheaves 29 carried by the frame 13 and running down to a winding drum 30 mounted on a shaft 31 that is carried by brackets 32 on the stationary frame 1. The winding drum is hollow and contains a spiral spring 33, the outer end of which is secured to the inner portion of the drum and tends normally to turn the drum in such direction as to wind up on the cable and thus elevate the frame 23, it being understood that the frame is adjustable vertically in accordance with the height of the stalks being cut. The periphery of the drum is provided with locking notches 34 arranged for the reception of a locking pawl 35 which serves to hold the drum 30 against the action of the spring and maintain the frame 23 in the position to which it is adjusted.

Mounted loosely on the pin 26 is a master gear 36 through which motion is imparted to the needle, and to the tying mechanism and to a shock embracing arm that assists in the shock-assembling operation. This gear is provided with two arcuate racks 37 and 38, the rack 38 intermeshing with a mutilated gear 39 that is secured to the upper end portion of the shaft 11, this shaft receiving motion first in one direction and

then in the opposite direction as the axle 2 is tilted up and down and the master gear is further provided with a segmental frame 40 carrying a smaller rack 41, which imposes movement to knot-tying mechanism in the manner hereinafter described. At the rear end of the frame 23 are two vertically disposed tubular sleeves 42 and 43 both of which are rigidly secured to and depend from the frame. Mounted on the sleeves are tubular shafts 44 and 45, respectively. The upper ends of the hollow shafts are provided with laterally extending arms 46 that are connected by a link 47 for mutual movement, the arms and links being so related that when movement is imparted to the sleeve 44 in one direction, the sleeve 45 will be rotated to the same extent, but in the opposite direction. The sleeve or shaft 44 carries a shock-engaging arm 48 and the shaft 45 carries a similar arm 49.

On the lower end of the rigid sleeve 42 is permanently secured a collar 50 from which projects an arm 51 that forms one of the bearings for a knotter shaft 52 hereinafter described. Between the collar 50 and the lower end of the sleeve or shaft 44 is arranged a revoluble collar 53, from which projects a radial arm 54, and said arm carries a depending finger 55 that is parallel with the axis of the sleeve 42. The shaft or sleeve 44 and the collar 53 are free for independent oscillatory movement to a limited extent, the excessive movement being prevented by a pin 56 depending from the lower end of the hollow shaft 44 and arranged to engage against the shoulders or walls of an arcuate recess 57 formed in the collar 53. Surrounding the hollow shaft 44 is a helical torsion spring 58, one end of which engages the arm 48 and the opposite end of which engages the arm 54, thus tending to separate said arm to an extent greater than approximately an angle of 90°. This however, will be prevented by the engagement of the pin 56 with the shoulder 59 of the recess 57 and limit the movement of the arm 48, while the arm 54 is engaged and held from further movement by a pawl 60 that is pivoted on a pin 61 extending upward from the arm 51. The pin is stationary and is provided with a diametrically arranged slot at its upper end for the reception of a straight strip of spring metal 62 which extends through a diametrically arranged slot formed in the head of a pin 63 that is carried by the pawl. The function of this spring strip tending to maintain the pawl in a position in the slot is such that the spring will always return the pawl to the central position, no matter in which direction the pawl may have been moved. When following out this construction, it may be observed that the knotter shaft 52 has an arm 64 which, when near

the completion of its single rotative movement, will engage the end of the spring 62 and will move the pawl 60 to released position, this movement occurring once during the cycle of operation.

The spring 58 will permit the arms 48 and 49 to move rearwardly slightly in case the arms are subjected to severe strain during the compression of a large shock. If the shock is small, however, the bottom spring is of sufficient strength to hold the arms against any rearward movement until the shock is ready to be discharged, and when the shock is in readiness for the discharge, the arm 64 of the counter shaft will move the pawl 60 to released position, so as to allow the arms 48 and 49 to move through an arc of 90° and allow the shock to pass from the machine.

Extending through the stationary hollow sleeves 42 and 43 are two hollow shafts 65 and 66, the shaft 66 carrying at its lower end a cord carrying needle 67 of hoop-like form. The hollow shaft 65 carries a shock embracing arm 68 which assists the needle in encircling and compressing the shock before the tying of the knot, this arm being much shorter, however, than the needle. The arm 68 is provided with an arcuate bar 69 curved on a line struck from the axis of the sleeve 42 and provided at one end with a vertically extending finger 70, which finger is arranged to engage against the finger 55 for the purpose of restoring the two arms 48 and 49 to normal positions, after the shock has been deposited upon the ground, this movement occurring during the downward movement of the forward portions of the plates 14.

In order that the operation may be made more clear, it may be stated that after a shock has been tied, the needle, and the arm which assists the needle remain in the dotted line positions shown in the drawings, and the arms 48 and 49 remain in a position at a right angle thereto until the plates 14 again start to tilt forward in the formation of another shock. During this forward movement of the plates 14, the needle and its auxiliary arm swing outward and in so doing the finger 70 of the auxiliary arm engages the finger 55 and turns the shock-supporting arms 48 and 49 back to normal positions so that they may be in position to receive the rear portion of a new shock, while the needle and its arm remain out of the way.

To the upper end of the shaft 65 is secured an arm 71 that is connected by a link 72 to a crank pin 73 carried by a gear segment 74 on the upper end of the shaft 66 and this gear segment 74 is arranged to intermesh with the rack 37 during the rotative movement of the latter, the gear segment serving to rotate the shaft through an arc of 180 degrees in one direction during the shock compressing and tying operation, and

- then back through the same arc in readiness for the reception of the stalks to form another shock. The movement of the shaft 66 is transmitted to the shaft 65 so that the auxiliary arm 68 is also operated in a direction the reverse of that of the needle, the needle and arm embracing the side and forward portion of the shock and compressing the same against the holding arms 48 and 49.
- 10 The gear segment 74 carries a peculiar form of stop, that is a modification of the well known Geneva stop. The segment is extended beyond the rack beam and is provided with a concaved face 75 that is curved 15 on an arc struck from the axis of the stationary pin 26 and this concaved face is arranged to engage with the smooth peripheral portion of the master gear after the rack 37 has moved out of mesh with the segment, so 20 that the master gear may continue its movement after completing the movement of the segment, for the purpose of subsequently transmitting movement to the knotting device, as hereinafter described.
- 25 In order to support the forward portion of the shock as well as to assist in discharging the finished shock, a cross bar 76 is employed. This cross bar has a central portion extending in a direct transverse line 30 across the machine, and its ends are turned or inclined as indicated at 77 to assist in guiding the shock into place. This bar is carried by a horizontally disposed bar 78 which is mounted in an elongated slotted guide bar 35 79 carried by an arm 80 that is bolted to the frame 23, the bar 78 and the slot in which it is mounted being of dove-tail form in cross section, in order to prevent displacement. This bar 78 will move forward 40 with respect to its guide 79 but its forward movement is limited by a pawl 81 that is pivoted in a bracket 82 extending from the arm 80 and entering a locking latch 83 in the bar 78. This particular portion of the 45 mechanism comes into play during the final discharge of the shock as will be herein-after explained.
- Extending through the hollow shafts 65 and 66 are two shafts 84 and 85 to which are 50 secured arms 86, the connection between the shafts and arms being preferably made by a set screw so that the arms may revolve adjustably on the shaft. To the outer end of each arm is pivoted a section 87 and to the 55 outer end of the section 87 is pivoted a section 88, the two pivots between the sections 86 and 87 and between the sections 87 and 88, being at a right angle to each other, and each including a clamping nut so that the 60 outer ends of the arms 86 may be adjusted both vertically and horizontally as required, the nuts being loosened and the sections of the arm moved to proper position after 65 which the nuts are firmly screwed in place to hold the sections in position. These arms 86 curve outward from the shaft and serve in connection with the arms 48 and 49 to support the stalks as the latter are discharged from the plates 14, some of the stalks falling rearward against the arms 86 and remaining 70 in that position, until the needle and its auxiliary embracing arm move around to gather the shock together.
- To the lower ends of the shafts 84 and 85 are secured additional arms 89 which are 75 also made of adjustably connected sections to permit of horizontal adjustment, and each of these arms 89 carries a long sleeve or roller 90 that is free to revolve on the arm proper during the discharge of the shock 80 from the machine, the rollers serving to reduce friction on the arms.
- The two arms 89 are brought in a plane to the rear of the plane of the arms 48 and 49 and normally do not come into play when 85 the shock is a relatively small one. If however, the shock is of large size, the compressing operation will force the arms 48 and 49 to the rear against the resilience offered by the spring 58, the spring yielding slightly 90 and permitting the arms to move until the shock comes into engagement with the arms 89, thus automatically enlarging the compression space in accordance with the size 95 of the shock. The arms 89 have been described as formed of adjustably connected sections and it is to be understood that under some circumstances these arms may be moved outward to a position at a right angle to that shown, that is to say, in positions parallel with the longitudinal axis of the machine, so that they will not come into contact with the shock under any circumstances. This modification of the apparatus, however, is intended more especially 100 for use where the shocks are delivered unbound and are allowed to fall upon the ground in the form of bundles to be afterward gathered together and tied in shock form, as more fully described hereinafter. 105 To the upper ends of the shafts 84 and 85 are secured beveled gears 90' which intermesh with beveled gears 91 on a horizontally disposed shaft 92 that is mounted in a bearing sleeve 93 rigidly secured to the upper plate 25 of the frame. Surrounding the shaft 92 is a helical torsion spring 94, one end of which is secured to the shaft, and the opposite end to the bearing sleeve 93. During the outward movement of the arms 89 115 to permit the discharge of the shock, the shafts 84 and 85 will be turned and the movement will be transmitted to the shaft 92 thereby placing the spring 94 under stress and this spring will thereafter revolve the 120 shaft in the opposite direction and return the arms to the initial position.
- The shaft 92 must be normally locked from movement in order to prevent the escape of the shock until the compression and 125 130

tying operation have been properly accomplished, as otherwise the compressing and tying of a large shock would move the arms to release position, and permit the premature escape of the shock. To accomplish this the shaft is provided with a disk 95 having a stop shoulder 96 which engages a pawl 97 that is pivoted on a bracket 98 projecting from the frame 23 and normally held in operative position by helical tension spring 99. The lower end of the pawl is connected by a wire or chain 100 to a bell crank lever 101 that is pivoted to the frame 23 and this bell crank lever is connected to the tail of the pawl 81 by a wire or chain 102, so that if the tail of the pawl is moved down, the movement will be transmitted to the pawl 97 and the latter will be moved out of engagement with the shoulder 96 of the disk and will be held out of engagement until after the shaft has been turned and the arms moved to open position to allow the discharge of the shock. After the discharging operation, the retractile force of the spring 94 will revolve the shaft 92 in the opposite direction, and restore the arms 89 to shock-holding position and at this time the pawl 97 will be free to again engage with the shoulder 96 of the cam and again lock the shaft until the completion of the next shock-tying operation. On the needle is a finger 103 which engages against one of the arms 89 as the needle moves to open position and thus positively returns the arms 89 to supporting position.

The knotter shaft 52 is supported in part by the lower bearing 51 and in part by an upper bearing 104 projecting from the frame 105, and at its lower end this shaft carries an ordinary form of knotting mechanism (not shown), to co-act with the needle or to operate upon the cord carried by the needle, in a manner common to binders or other machines of that type. To the upper end of the shaft 52 is secured a gear 105' which intermeshes with a gear wheel 106 of the same diameter, the gears making a single complete revolution at each operation, and always stopping at the end of the operation with the arm 64 in the position indicated.

The gear 106 is mounted on a shaft 107 which carries a mutilated gear 108 that intermeshes with the rack 41. The gear 108 carries a ratchet pin or arm 109 that projects beyond the periphery of the wheel and toward the latter part of the movement is engaged by a pin 110 at the end of the rack, for the purpose of completing a full rotative movement of the gear 108. In the operation of this portion of the mechanism, the rack 41 is moved and the first tooth of the mutilated gear engages the first tooth of the rack, the mutilated gear being turned until its last tooth engages the last tooth of the rack, and by this time it has nearly completed a revolution. The pin 110 then engages the

rigid arm 109 of the mutilated gear and carries the latter farther around until the complete revolution is effected, and the pin 110 has passed beyond the arm 109 leaving the uncoothed portion of the mutilated gear facing the rack. The master gear then starts on its return movement, which occurs when the plate 14 is coming to dumping position, without turning the gear and without rotating the knotter in a backward direction. In order to prevent this backward rotative movement, the shaft 107 carries a disk 114 having a stop shoulder 115 with which engages a spring pressed pawl 116 so that the shaft and mutilated gear will be positively held. The operation of the tilting plate 14, discharging, shock-assembling and tying mechanisms as described contemplates the movement of the arm 4 by the rearward movement of the draft mechanism, that is to say, by the backing of the horses and the transmission of this movement to the arm 4 through the connecting bar 5. Obviously this movement may be effected by the use of any other suitable mechanism, if so desired.

The mechanism thus far described operates to assemble the stalks and bind the stalks in the form of a shock, and as a result of the operations of this mechanism, the upper portion of the shock is embraced by the needle and the auxiliary arm, and is resting against the rear arms of the upper frame 23. The butt ends of the stalks are divided into four columns two being located at each end of the plate 20 and the two at each end of the said plate being separated from each other by the levers 22 as well as the fingers 18, although the latter are about to be withdrawn and have no further function. The bundles behind the levers 22 are resting on the ground, while the bundles in front thereof are still resting wholly or in part on the spreader boards 15.

It now becomes necessary to eject or discharge the shock from the machine, and to further spread the several bundles or columns so as to insure the stability of the shock and to provide for ventilation. The upper portion of the shock is engaged by the transversely extending bar 76, this bar being carried by the horizontally guided bar 78 and the said bar 78 is provided with the projecting lug 117, said lug having a rectangular opening for the passage of a correspondingly shaped bar 118, the lower end of which is bifurcated and is rigidly secured to an ejector frame 119.

The ejector frame includes a horizontally disposed bar 120 that is arranged at a point near the longitudinal center of the machine, its rear end being guided in an opening formed in a bracket 121 projecting from the fixed frame 1. From the rear end of this bar depends an arm 122 to the lower end of

which is secured a lower ejector bar 123 that is disposed immediately above the plate 20 and is bent forward and thence outward at points beyond the side bars of the main frame 1 to form arms 124 that are disposed normally at the juncture of the plates 14 and the spreader plates 15 so that if the ejector frame is moved rearward, or is allowed to remain perfectly stationary, while the remainder of the machine moves forward, the upper portion of the shock will be engaged by the bar 76 and the forward bundles of the shock will be engaged by the ejector arms 124 and the shock will be positively ejected from the machine. In the operation of this portion of the mechanism, the ejector frame remains perfectly stationary, while the ejector bar and arms rest against the forward face of the shock. The remainder of the machine then moves forward a slight distance and travels away from the shock, so that the latter being held stationary will be positively ejected from the machine.

In order to arrive at a clear understanding of the operation of the ejector, it is first necessary to consider the mechanism by which the ejector is held stationary, while the remainder of the machine travels forward. The ejector frame 119 is provided with a forwardly extending bar 125 that is guided in any suitable manner, and is disposed to one side of the central longitudinal axis of the main frame. To this bar is pivoted an anchor 126, the anchor being mounted at its forward end on a pin 127 that is carried by a bracket 128 on the bar 125. The downwardly projecting spur or cleat 129 of the anchor is arranged to be embedded in the ground, so that the ejector frame will be held stationary, while the remainder of the machine is free to move forward. Near the upper rear end of the spur or cleat is a shoulder 130 that is arranged to be engaged by a pawl 131 that is carried by a lever 132 pivoted on the arm 125, and this pawl is normally held in an engaging position by a spring 133. From the upper portion of the pawl projects an operating rod 134 which is under the control of the operator, and by pulling this rod forward, the anchor may be released and allowed to move downward and into engagement with the ground.

The bar 125 carries an upwardly extending bracket 135 having a bearing for the reception of a shaft 136 and on this shaft is secured a lever having two arms 137 and 138. Pivoted to the upper arm 138 is a block 139 having an opening for the passage of a curved rod 140, the rear end of which has an enlarged head 141, that is brought into engagement with the block in order to move the latter forward at times. The forward end of the rod 140 is connected to a crank pin carried by a crank 141' on a crank shaft

142 of mechanism 175 driven by a motor 176. During the forward travel of the machine and after the machine stops and the plates 14 are tilted and the shock gathered and tied, the shaft 142 makes one complete revolution. This results, of course, in a single complete revolution of the crank 141' and the latter moves in the direction indicated by the arrows, the head 141 of the rod 140 engaging the rear face of the block 139 and moving the upper end of the lever forward after which the crank arm 141' resumes its original position.

Pivoted to the anchor at a point about midway of the ends of the latter is an arm 143 having an elongated slot 144 in its upper portion and through this slot extends a pin 145 that projects from the lower arm 137 of the lever, this pin being preferably provided with an anti-friction roller that rides against the walls of the slot. Engaging the lower face of the anti-friction roller is a washer 146 and between this washer and the lower washer of the arm is a helical compression spring 147 that is placed under stress as the lever moves, the spring tending to force the finger downward, but movement being prevented by the pawl 131 until said pawl is moved to released position by the pulling strain on the operating rod 134. It will be noted that when the lever is moved to set the spring, the crank pin 145 is carried to a position to the rear of the vertical plane of the axis of the shaft 136 and as the pivotal connection between the arm 143 and the anchor is in this vertical plane, the parts will be locked and the lever arm 137 will move against a fixed stop lug 148 carried by the bracket 135 so that the spring cannot act to turn the lever and its force becomes effective only when the pawl is released, whereupon the spring is expanded and drives the anchor into the ground, so that the ejector frame will now be held perfectly stationary, while the remaining portion of the machine moves forward and this movement is permitted without further operative engagement with the spring setting lever, owing to the sliding connection between the operating rod 140 and the block 139.

Extending between the ejector frame and the fixed lug 149 on the main frame 1, is a helical tension spring 150 which is placed under stress during the relative movement of the ejector frame and the main frame of the machine, and when the operation of the ejector is complete, this spring will serve to return the ejector frame to its initial position.

On the main frame of the machine is arranged a vertical arm 151 having a laterally extended finger 152, which as the frame moves forward will engage the lower arm 137 of the spring seated lever and will move the same forward past its dead center, thereby

breaking the lock, or moving the crank pin 145 forward of the vertical plane of the axis of shaft 136 so that the anchor depressing spring 147 is then free to fully expand, 5 and the washer 146 at the upper end of the spring will act on the pin 145 and tend to move the spring seating lever back to normal position. This movement is assisted by an auxiliary torsion spring 153 which surrounds the 10 pivot pin 127 of the anchor and is connected at one end to the ejector frame and at the opposite end to the anchor. The torsion spring is much lighter than the anchor depressing spring and is placed under stress 15 as the latter exercises its force in driving the anchor into the earth. When, however, the setting lever is drawn beyond the center and the anchor depressing spring is no longer retracted, the spring 153 will operate to 20 raise the anchor out of the ground and restore the same to the initial position, the anchor moving up until its shoulder 130 is automatically engaged and locked by the pawl 131.

25 Before the ejector operation is accomplished and the ejector frame resumes its normal position, there is considerable strain on the ejecting mechanism due to the subsequent operation of spreading the base of the 30 shock, as will hereinafter appear, and to guard against any further rearward movement of the ejector, provision is made for locking the same to the fixed frame until the parts are ready for another operation.

35 On the fixed frame of the machine is a bar 154, said bar carrying a forwardly projecting arm 155 and this arm carries two pins 156 and 157, the axes of which are in the same horizontal plane. On the pin 156 is 40 pivoted an ejector locking lever 158, the forward end of which is in the form of a pawl and is arranged to engage in a recess 159 in the upper face of the bar 125 of the ejector and the said lever is held in locking position 45 by a spring 160 extending between the pin 157 and a second pin 161 on the lever, the longitudinal axis of the spring being in a plane above the axis of the pivot pin 156 so that the locking lever will be automatically 50 held in locking position. When the locking lever is moved out of engagement with the ejector, the spring passes below the axis of the pin 156 and thereupon holds the lever in release position. The rear end of 55 the lever has a shoulder 162 that is arranged to engage a pin 163 on the anchor, and is further provided with a cam 164 that is arranged to be engaged by said pin as the anchor moves upward.

60 The normal position of the parts after setting the spring 147 is then indicated in the drawing, and when the rod 140 is moved forward and the operating rod 134 is pulled and the anchor released and driven into the 65 ground, the pin 163 will pull downward on

the shoulder 162, thus tilting the locking lever and raising its forward end out of engagement with the locking recess 159, while the spring 160 will thus hold the locking lever in released position. This movement is 70 further assisted by an arm 165 that projects from the upper portion of the pawl lever 132 and is brought into engagement with the rear end of the locking lever as the pawl lever moves to release the anchor, so that 75 the locking lever is compelled to move to released position. When the anchor moves upward, the pin 163 engages the cam surface 164 of the lever, and tends to raise said lever up to such position that the axis of the 80 spring 160 will be thrown above the axis of the pin 156 so that the lever will be moved down to engaging position and the parts will be automatically locked, ready to resist the strain that tends to pull the ejecting mechanism rearward. 85

In following out the ejecting operation it will be remembered that the pawl 81 normally rests in the recess 83 of the bar 78 and when the frame which carries the pawl 90 moves forward, while the ejector bar 78 remains stationary, the pawl rides up out of the recess and exerts a downward pull on the wire 102, this movement being transmitted through the connecting parts to the 95 pawl 97 which releases the disk 95 and allows the shaft 92 to turn for the purpose of permitting the shock-engaging arms 89 to release the rear portion of the shock. At the same time the arms 124 of the ejector 100 remain stationary, while the frame moves forward, and these arms engage the forward bundle columns of the shock and hold the same while the machine moves forward, so that these bundles will be moved from the 105 spreader plate 15 and the base of the shock will then move down so that all of the column bundles rest on the ground. The forward movement of the frame will of course, carry the plate 20 forward, and as a result 110 of this the levers 22 will act to separate the forward bundles of the shock from the rear bundles of the shock, and subsequently will operate to separate the forward bundles from each other. The two levers 22 are 115 pivoted to arms 166 that project rearward from the main frame, and the pivot pins 167 of these levers are surrounded by torsion springs 168 each having one end engaging the arm 166, the function of the spring 120 being to restore the levers 22 to positions at right angles to the longitudinal plane of the machine after the levers are clear of the shock. The inner arms of the levers are connected together for mutual movement, 125 one of them having a pin 169 and the other a slot for the reception of the pin. To the inner arm of one lever is connected a link 170 which extends to a lever 171 that is pivoted on a pin 172 carried by the under side 130

of the plate 20, both the lever and link being provided with a plurality of openings in order to permit adjustment of the points at which they are pivotally connected. That 5 end of the lever 171 opposite the link is provided with an upwardly projecting pin 173 that extends through an arcuate slot 174 arranged on a curved line struck from the axis of the pin 172 and this pin engages a 10 yoke 175 formed in the cross bar 123 of the ejector, and it is through this connection that the strain on the ejector frame is transmitted during the spreading of the base of the shock.

15 When the parts are in the positions just at the commencement of the ejecting operation, the levers 22 extend out at right angles to the longitudinal plane of the machine. The ejector bar then remains stationary, while the frame moves forward, and during the preliminary portion of this movement, the levers 22 will still be held in the first mentioned position so as to move the forward column bundles away from the 20 rear bundles. By the time the pin 173 has reached the end of the slot 174, the levers 22 will then have swung rearwardly at their outer ends so that they will brush against the inner sides of the forward column bundles of the shock and spread them further apart, so that the base of the shock has four 25 widely spaced points of support to insure its stability and to permit free passage of air therethrough.

30 35 I claim:—

1. In shock forming apparatus, pairs of oppositely extending arms arranged to swing in horizontal planes and forming a support for the rear of the shock, a shaft 40 carrying each pair of arms, bevel gears at the upper ends of said shafts, a horizontally disposed shaft having bevel gears intermeshing with those of the arm carrying shafts, a spring encircling the horizontal shaft, a 45 shouldered locking disk on the horizontal shaft, a locking pawl engaging said shouldered disk, means for laying the bundles of stalks against the arms, means for compressing the stalks into shock form against 50 the inner arms, a shock ejector arranged to engage the forward face of the shock, a pawl actuating means under the control of the ejector and serving to move said pawl to release position, the spring being placed 55 under stress during the turning of the shafts and arms to free the shock and serving to restore said arms to initial position after the discharge of the shock.

60 65 2. In shock forming apparatus, pairs of oppositely extending arms arranged to form a support for the rear of the shock, vertical shafts carrying said arms and provided with bevel gears, a horizontal shaft having bevel gears intermeshing with those of the vertical shafts, a torsion spring carried

by the horizontal shaft, a shouldered locking disk on said horizontal shaft, a pawl engaging said disk, a shock ejector engaging the forward end of the shock and including a notched bar, a pawl arranged to engage 70 the notch in said bar, means for sliding the ejector rearwardly to eject the shock, thereby raising the pawl out of said notch and releasing the first mentioned pawl, connecting means between the two pawls, the 75 spring being placed under stress during movement of the arms to free the shock and serving to restore said arms to initial position after each shock discharging operation, means for laying bundles of stalks against 80 the arms, and means for compressing the stalks against the inner ends of said arms to form a shock.

3. In shock forming apparatus, pairs of oppositely extending arms arranged to form 85 a support for the rear of the shock, vertical shafts carrying said arms and provided with bevel gears, a horizontal shaft having bevel gears intermeshing with those of the vertical shaft, a torsion spring on the horizontal shaft, a shouldered locking disk on said shaft, a locking pawl engaging said disk, an ejector in front of the pairs of arms and adapted to engage the front of the shock, 90 means operated by the ejector for releasing the locking pawl from the disk, a needle, and an auxiliary arm serving to encircle the stalks and compress the same against the inner arms of the pairs, hollow shafts carrying the needle and auxiliary arm, and encircling said vertical shafts, means for connecting the hollow shafts for mutual movement, and an arm or lug carried by the needle and arranged to engage the inner arm of 95 one of said pairs to force the same back to 100 initial position after each shock discharging operation.

4. In shock forming apparatus, pairs of oppositely extending arms against which the stalks rest during the shock forming operation, vertical shafts carrying said arms, means for connecting said shafts for mutual movement, a pair of hollow shafts encircling 110 said vertical shafts, a hook like needle mounted on one of the hollow shafts, an auxiliary arm carried by the other hollow shaft and co-acting with the needle in compressing the shock, a gear segment carried by the needle shaft, a crank pin on said gear segment, a crank arm on the other hollow 115 shaft, a link connecting the crank arm to the crank pin, a master gear arranged to engage the gear segment and impart movement to the needle, means for locking the two pairs of arms from movement, said means including a notched disk geared to the arms, and a pawl normally engaging the disk, an ejector, a second pawl, a connection between the two pawls, and means operated by the 120 ejector when moving in one direction for 125 130

shifting said second pawl to actuate the other pawl and release the disk and the pairs of arms.

5. In shock forming apparatus, a pair of vertical hollow shafts, arms carried by said shafts and forming a support for the rear of the shock, means for connecting said shafts for mutual movement, a locking device for the shaft, a needle, an auxiliary arm, a connection between the needle and auxiliary arm for shifting them toward each other to encircle and compress the stalks against said arms to form a shock therebetween, a knotter shaft, and means on the knotter shaft for 10 releasing the arms and permitting the discharge of the shock.

6. In shock forming apparatus, a pair of vertical hollow shafts connected for mutual movement, arms carried by said shafts and arranged to form a support for the rear of the shock, a needle, an auxiliary arm, said needle and auxiliary arm each being curved to extend partly around a shock being formed, a connection between the needle 15 and auxiliary arm, means for swinging said auxiliary arm toward the needle during the movement of the needle toward the shock, thereby to compress the stalks between the auxiliary arm and the needle and against 20 said arms in the form of a shock, means for locking said arms in position during the shock pressing operation, a knotter shaft, means thereon for releasing the arms and allowing discharge of the shock, and means on 25 the auxiliary arm for restoring the shock supporting arms to initial position after each discharging operation.

7. In shock forming apparatus, a pair of vertical hollow shafts connected for mutual movement, a pair of arms carried by said shafts and normally extending toward each other to support the rear of the shock, a finger extending laterally and downwardly from one of said shafts, a curved 40 needle, means for swinging the needle horizontally toward the bundles to embrace one side of the shock, an auxiliary arm at the other side of the shock, a connection between the needle and arm for drawing said arm toward the shock and needle thereby to encircle and compress the stalks against said supporting arms to form a shock, a locking device engaging one of the hollow shafts, a lock releasing member, a knotter shaft carrying said lock releasing member, and a lug 45 extending from the auxiliary arm and arranged to engage the finger of the hollow shaft to thereby restore the supporting fingers to initial position after each discharging operation.

8. In shock forming apparatus, a pair of vertical hollow shafts connected for mutual movement, arms carried by said shafts and normally extended toward each other to 50 support the rear of the shock, a collar dis-

posed below one of said shafts, an arm extending from the collar, a torsion spring surrounding the shaft and tending to separate the arm of the collar and the arm of the shaft, a finger extending laterally and downwardly from the shaft, a pawl arranged to engage the collar arm and serving to hold the arms in shock supporting position, a pawl holding spring, a revolute shaft, an arm carried thereby and arranged to engage the pawl spring and move said pawl to release position, means for laying bundles of stalks against the arms, a horizontally movable needle, means for swinging said needle toward the bundles to embrace one side of the shock, an auxiliary arm at the other side of the bundles, a connection between the needle and auxiliary arm for shifting said arm toward the needle and shock during the movement of the needle toward the shock, thereby to compress the stalks against the arms to form a shock, and a lug carried by the auxiliary arm and arranged to engage the laterally and downwardly extending finger for restoring the shock supporting arms to initial position after each shock discharging operation.

9. In shock forming apparatus, a frame, a pair of depending tubes rigidly secured to the frame, vertical hollow shafts encircling said tubes, rocker arms extending from said shafts, a link connecting the rocker arms, a pair of shock supporting fingers carried by said hollow shafts, said fingers and shafts being yieldable to a limited extent, hollow shafts extending through the tubes, a needle carried by one of the hollow shafts, an auxiliary arm carried by the other hollow shaft and coacting with the needle in compressing the shock, a gear segment secured to the needle shaft, a crank pin on the segment, a rocker arm secured to the opposite hollow shaft, a link connecting the rocker arm to the crank pin, a master gear 95 having rack teeth arranged to engage the segment, a pair of solid shafts extending through the inner hollow shaft, bevel gears at the upper ends of said solid shafts, a horizontally disposed shaft having bevel 100 gears intermeshing with those of the solid shafts, and a torsion spring on said horizontal shaft, a locking disk on the horizontal shaft, a pawl engaging said locking disk, a horizontally movable ejector, a second 105 pawl adapted to be actuated thereby, a connection between the two pawls for releasing the first named pawl, sectional levers secured to the lower ends of the solid shafts, said levers being normally disposed in approximately parallel relation with the shock supporting arms, and arranged to receive the rear end of the shock when the yieldable arms move rearward, and automatic means controlling the movement of the ejector. 110 115 120 125 130

10. In combination, a wheeled frame, shock forming mechanism carried thereby, a horizontally movable shock ejector in front of the shock forming mechanism, a pivotally mounted anchor for connecting the ejector to the ground, and holding the same from forward movement, while the remainder of the machine moves forward, and means for automatically raising the anchor 10 and restoring the ejector to normal position.

11. In combination, a wheeled frame, shock forming mechanism carried thereby, a shock ejector, an anchor normally in inoperative position, means for locking the anchor in such position, means for releasing the held anchor, a spring for forcing the anchor down when released to hold the ejector while the remainder of the frame 20 moves forward, and means for automatically raising the anchor and restoring the ejector to normal position.

12. In combination, a wheeled frame, shock forming mechanism thereon, a shock ejector, an anchor for holding the ejector, means for locking the device to hold it normally in inoperative position, a spring normally bearing downwardly on the anchor, means for setting the spring for moving the 30 locking device to release position, to allow the spring to force the anchor into the ground, and means for restoring the anchor and ejector to initial position.

13. In combination, a wheeled frame, shock 35 forming mechanism thereon, a shock ejector, an anchor pivoted to the ejector, a locking pawl for holding the anchor in elevated position, a lever, a pin extending therefrom, a rod pivoted to the anchor and having an 40 elongated slot for the reception of said pin, a spring encircling the rod and bearing against the pin, means for turning the lever to compress or set the spring, and means for tripping and holding the pawl and allowing the anchor to descend under action 45 of the spring.

14. In combination, a wheeled frame, shock forming mechanism carried thereby, an ejector, an anchor pivoted to the ejector, 50 an anchor holding pawl, a two armed setting lever, a pin projecting from one of the arms, a rod pivoted to the anchor and having an elongated slot for the reception of the pin, a spring surrounding the rod and bearing at one end against said pin, means 55 engaging the opposite arm of the lever and serving to turn the same to compress the spring, a stop for limiting movement of the setting arm, and means for moving the 60 pawl to release position.

15. In combination, a wheeled frame, shock forming mechanism thereon, a shock ejector, an anchor pivoted to the ejector, a holding pawl for the anchor, a two armed 65 lever, a pin projecting from one of the arms,

a rod pivoted to the anchor, and having an elongated slot for the reception of the pin, a spring encircling the rod and bearing at one end against the pin, means engaging the opposite arm of the lever and serving to 70 turn said lever to spring setting position wherein the pin passes to locking position slightly beyond the common plane of the axes of the rod and lever, a stop with which said lever engages, means on the wheeled 75 frame for breaking the lock joint after the anchor has been depressed, and an anchor elevating spring tending to restore the anchor to its elevated position.

16. In combination, a wheeled frame, 80 shock forming mechanism thereon, a shock ejector, an anchor pivoted to the ejector, a spring bearing downwardly upon the anchor and movable with the ejector, a locking pawl for locking the anchor in elevated 85 position, a lever for setting the anchor spring, a block pivoted to said lever and provided with an opening, a headed rod passing through the opening, a crank shaft, and a crank arranged on the shaft and carrying said rod and serving to transmit 90 spring setting movement to the lever.

17. In combination, a wheeled frame, shock forming mechanism thereon, a shock ejector, a slid able frame carrying the ejector, said frame having a locking notch, a locking lever pivotally mounted on the wheeled frame and having one end arranged to enter said notch, an anchor pivoted to the 100 ejector frame, a holding pawl for the anchor, a pin carried by the anchor and arranged to engage a shoulder of the lever, a spring acting on the lever and extending past the fulcrum thereof, said spring operating to hold the same when moved to 105 either side of its dead center to either locked or unlocked position, and an arm projecting from the pawl and arranged to engage and move the lever to release position when the 110 pawl is moved to release the anchor.

18. In combination, a wheeled frame, a vertically adjustable shock compressing and binding mechanism, an ejector bar movable vertically with said mechanism, an ejector frame slid able with respect to the wheeled 115 frame, a vertical bar extending from the ejector frame, a slid able connection between the vertical bar and the ejector bar, lower ejector bars or arms carried by the ejector frame, and means for holding the ejector frame from movement while the wheeled 120 frame moves forward.

19. The combination with a wheeled frame, of a slid able ejector frame, means for anchoring the ejector frame to the 125 ground, while the wheeled frame moves forward, a rearwardly extending plate carried by the frame, a pair of pivoted spreader arms carried by the plate, a pair of ejector bars connected to the ejector frame and lo- 130

cated in advance of the spreader arms, a cross bar carried by the ejector and having a yoke, a lever, a pin upstanding from the lever, and connections between the lever and the spreader arms, said cross bar being adapted to slide with the ejector, said arms being movable to angular positions during such movement.

20. The combination with a wheeled frame, of an ejector bar arranged at the rear portion of the frame, a pair of pivotally mounted spreader arms arranged to engage with the butt ends of the stalks, the inner ends of said arms being pivotally connected to each other, a cross bar carried by the ejector and having a yoke, a lever, a pin upstanding from the lever, and connections between the lever and the spreader arms, said cross bar being adapted to slide with the ejector, said arms being movable to angular positions during such movement.

21. A shock forming machine including means for depositing the shock in an upright position with its rear portion on the ground,

and means for holding and laterally spreading the shock after such depositing and means for gradually depositing the front portion of the shock upon the ground during the forward movement of the machine.

22. A shock forming machine including a main frame, a plate projecting from the rear end thereof, and means for depositing a shock in upstanding position with its forward portion on the plate, said means including an ejector bar located above and transversely of the plate, said bar having a yoke, a shock spreading lever, and means engaged by the yoke during the first portion of the next movement of the machine, to actuate the spreading lever to spread a shock.

In testimony that I claim the foregoing as my own, I have hereto affixed my signature in the presence of two witnesses.

LUTHER T. VELEN.
